UNITED STATES PATENT OFFICE.

LOUIS PFINGST, OF PULLMAN, ASSIGNOR TO GEORGE M. PULLMAN, OF CHICAGO, ILLINOIS.

PIVOTAL SUPPORT FOR SASHES.

SPECIFICATION forming part of Letters Patent No. 351,936, dated November 2, 1886.

Application filed January 21, 1886. Serial No. 189,318. (No model.)

To all whom it may concern:

Be it known that I, LOUIS PFINGST, a citizen of the United States, residing at the village of Pullman, in the county of Cook and State of Illinois, have invented a new and useful Improvement in Pivotal Bearings for Sashes, for which I desire to secure Letters Patent of the United States, and of which the following is a specification.

10 The object of my invention is to provide such a pivotal mounting for sashes used in the roofs of street and railway cars as ventilators, in transoms, and similar places as shall permit free pivotal movement of the sash, and 15 also operate to hold the sash with sufficient firmness and stability in any position in which it may be placed, and which shall also be cheap of construction, simple, and not likely to get out of order. To this end I propose to 20 provide the sash at each end with pivotal extensions or shafts, and to place between each of the said pivotal extensions and the socket provided therefor in the frame-work of the casing, about the opening filled by the sash, 25 springs, attached, preferably, to the pivotal extension and bearing upon the socket, or, if preferred, attached to the socket and bearing upon the pivotal extension, so as to furnish a certain amount of resistance to the turning of 30 the sash—that is, not enough to prevent its being readily changed from one position to another, but enough to hold it in any position in which it is placed against displacement 35 from the jarring of the car, or from similar causes.

In the drawings forming part of this specification, Figure 1 shows a sash in position having one of my pivotal bearings at each end. Fig. 2 is a cross-section of one of the 40 pivotal bearings, showing it in position in its socket. Fig. 3 is a modification of the same, and Fig. 4 another modification, in which the spring is attached to the socket instead of to the pivotal extension. Fig. 5 is a cross-section taken on the line 5 5, Fig. 1.

The essential feature of my invention consists in the spring E, lying between the pivotal extension B from the sash and the socket A. This spring may assume a variety of 45 forms, all of which are within my invention. Thus it may be a single spring passed through a central slot in the extension B and curving

about it, as shown in Fig. 2, or it may be a double spring attached by a bolt or rivet to the extension B, as shown in Fig. 3, or it may be attached to the interior of the socket, clasping the extension, as in Fig. 4; and many other obvious modifications might readily be suggested. The pivotal extension B may be attached in any desired manner to the sash. I prefer using a plate, C, screwed to the face of the sash and bent at right angles across its edge, the pivotal extension projecting from the latter part of the plate. This construction permits the point of attachment of the plate to the sash to be on the outer surface of the sash, and therefore considerably more convenient of access. It also gives a firmer setting for the pivot than where the plate to which the latter is attached is secured merely to the edge of the sash.

I am aware that it has been heretofore proposed to use pivotal bearings for sash in connection with springs of various forms. My invention consists in the application of a spring of circular form attached either to the pivot or to its socket, and bearing against the inner concave surface of the socket, or clasping the pivot, according to its location. This construction gives the largest possible frictional surface, giving a higher degree of stability to the sash in any position in which it may be placed than has been attained by the constructions previously used.

I claim—

1. In a sash-bearing, the combination of a pivotal extension; a socket therefor, and a spring of circular form attached to one of the said parts and bearing upon the other, substantially as described and shown.

2. In a sash-bearing, the combination of a pivotal extension, a socket therefor, and a spring of circular form attached to the pivotal extension and bearing outward upon the concave interior of the socket.

3. As a sash-bearing, the combination of plate C, bent at right angles and having projecting from it the pivotal extension B, in combination with a socket and a spring, substantially as described and shown.

LOUIS PFINGST.
